Application March 1, 1933, Serial No. 659,119

10 Claims. (Cl. 171—119)

My invention relates to compensating means for automatic regulators and has particular relation to line-drop compensators employed with voltage regulators connected in open delta relation in 5 three-phase power transmission and distribution circuits.

Because automatic feeder voltage regulators are usually located at some distance from the point of power distribution at which it is desired 10 that the voltage be maintained constant, it is necessary to provide means for compensating the control of the regulators in accordance with the voltage drop in the feeder circuit. This voltage drop varies in accordance with the current flowing 15 in the circuit and is the vector sum of the resistance and reactance components of voltage drop in the circuit impedance. To effect such compensation, a device known as a line-drop compensator is employed in the control circuit 20 of each regulator operating means.

Such a line drop compensator is in effect a duplication in miniature of the line from the regulator to the point of load distribution. Through it a current is passed that is proportional 25 to the line current and which causes a voltage drop across it that is proportional to the line drop in voltage. From a measure of this voltage drop, the regulator adjusts itself to maintain the proper voltage at the distant distribution center.

30 In the application of induction or other voltage regulators to three phase, three-wire circuits, only two single-phase regulators per circuit need be utilized, they being connected in well known manner in an open delta connection. In such a three-phase system the line current is at unity power factor 30° out of phase with the line-to-line voltage. Consequently, there is a 30° phase displacement between the readily available voltage and current quantities which may be utilized 35 to respectively control each regulator and to energize the line-drop compensator therefor.

In the past, it has been deemed necessary to 40 employ special means for bringing the compensator energizing current at unity power factor of the regulated circuit in phase with the circuit voltage which is impressed upon the regulator control circuit, to effect proper operation of the compensating system. One well known practice for attaining this result is to insert a third current transformer in the common phase conductor of the open delta regulator connection which, when interconnected with the current transformers in the other phase conductors, provides currents having the proper phase relation with 45 respect to the available line-to-line voltages.

More recently, to eliminate the third current transformer in the common lead, an auxiliary device known as a compensator phase angle transformer has been utilized. Both of these schemes are, however, expensive, the first because it involves not only the cost of the extra current transformer but also its installation which sometimes requires additional structures, and the second because it entails the expense of a special piece of equipment and necessitates control circuit inter- 60 connections between the two regulators.

55 My invention is directed to an improved compensating system, especially adapted for use in connection with open-delta-connected regulators of the type under consideration, which eliminates the disadvantages above named and which possesses additional advantages to be particularized hereinafter.

One object of my invention is to provide a line-drop compensating system for automatic voltage 75 regulators connected in open delta in three phase circuits that is simple in construction, inexpensive to build, and that requires a minimum amount of equipment.

A further object of my invention is to provide 80 means whereby a line drop compensator utilized with a voltage regulator may be directly energized by a current which bears a predetermined phase displacement with respect to the circuit voltage impressed upon the regulator control circuit. 85

Another object of my invention is to provide 90 a compensating system for open delta connected regulators which requires no control circuit interconnections between the two single phase regulators utilized.

I have discovered that in the case of an automatic voltage regulator application, where the line current readily available for compensator energization is displaced, at unity power factor, by 30° from the line-to-line voltage from which the 95 regulator operating means derive control, if the resistance and reactance elements of the compensator are properly adjusted not as in accordance with the prior practice to be proportional, respectively, to the resistance and reactance components of line impedance but in a special manner to be more completely described, the operation of the compensator will be exactly the same as were an in-phase energizing current to be utilized with the settings of the compensator elements proportional to the line components of impedance. Hence, by setting the compensator in accordance with the teachings of my invention, the special phase shifting equipment and the interconnection of the regulator control 100 105 110

circuits heretofore required in open delta applications may be entirely dispensed with, thereby allowing marked savings in the cost of the compensating equipment and corresponding advances in the simplicity thereof to at once be effected.

My invention will be best understood through the following description of specific embodiments thereof when taken in conjunction with the accompanying drawings, in which:

Figure 1 is a diagrammatic view of apparatus and circuits illustrating the simplified compensating system of my invention applied to each of two single phase automatic voltage regulators disposed in open delta relation in a three-phase transmission circuit,

Fig. 2 is a diagram of vectors illustrating the phase angle relation, at unity power factor, of the voltages and currents acting in the several phases of the transmission circuit shown in Fig. 1,

Fig. 3 is a vector diagram illustrating the effective voltage drops, at unity power factor, through the impedance of the transmission line which must be compensated for in controlling each of the regulators of Fig. 1,

Fig. 4 is a vector diagram illustrating the manner in which special settings of the resistance and reactance elements of the compensators of Fig. 1 permit these simplified compensating devices to satisfactorily function when energized by currents displaced, at unity power factor, by 30° from the voltages impressed upon the regulator control circuit,

Fig. 5 is a vector diagram showing that when the compensator energizing current lags the voltage by 30° the special settings of the compensator elements provided by my invention are such that the phase angle of the compensator impedance is 30° greater than the phase angle of the compensated line or transmission circuit impedance,

Fig. 6 is a vector diagram similarly illustrating the proper settings of the compensator energized by a current which leads the voltage by 30° as those in which the compensator phase angle is 30° less than the angle of the line impedance,

Figs. 7 and 8 are vector diagrams showing the current and voltage relations in the three phase transmission circuit for lagging and leading power factor loads thereof respectively and illustrating that changes in power factor have no effect upon the special settings of the compensator elements,

Figs. 9 and 10 are vector diagrams showing that when the phase angle of the impedance of the line to be compensated lies outside of a given range of values the compensator adjusted in accordance with my invention must supply negative values of resistance and reactance respectively,

Fig. 11 is a diagrammatic view of apparatus and circuits illustrating means for enabling a simplified compensator of the type illustrated in Fig. 1 to supply either positive or negative values of resistance and reactance,

Fig. 12 is a similar representation of component reversing means applied to a compensator of a well known rotary contactless type.

Fig. 13 is a diagrammatic representation of apparatus and circuits illustrating a special interconnection of the two current transformers which energize the compensators of the two regulators disposed in open delta which causes the energizing current of both compensators to lead, at unity

power factor, the associated line-to-line voltage by 30°,

Fig. 14 is a vector diagram illustrating the manner in which this leading current is supplied to the compensator associated with the line in which the main circuit current lags the line-to-line voltage by 30°,

Fig. 15 is a diagrammatic representation of apparatus and circuits illustrating an interconnection of the two current transformers which causes the energizing current of both compensators to lag, at unity power factor, the corresponding line-to-line voltage in the three-phase circuit by 30°, and

Fig. 16 is a vector diagram illustrating the manner in which the lagging current is supplied to the compensator associated with the line in which the main power current leads the associated line-to-line voltage by 30°.

Referring to the drawings and particularly to Fig. 1 thereof I have there illustrated two voltage regulators 10 and 12 of a well known induction type connected in open delta relation in a three-phase transmission circuit which comprises line conductors A, B and C, shown as terminating at

a point distant from the regulators. The two regulators 10 and 12 respectively comprise series windings 14 and 15 connected to introduce corrective voltages into transmission circuit conductors A and B, respectively, to thereby modify the circuit supply source potentials, and exciting windings 16 and 17 energized by the voltages acting between the common line conductor of the open delta regulator connection and the two outer line conductors with which the two regulators 10 and 12 are respectively associated. It will be understood that in a regulator of this type, the magnitude and direction of the corrective voltage introduced by the series winding is controlled by varying the inductive relation of the series and exciting windings, such as by mechanically moving or rotating the plane of one winding with respect to the plane of the other.

As shown, regulators 10 and 12 are respectively operated by means of reversible motors 20 and 22 mechanically connected thereto through suitable gearing. The motors 20 and 22 are similar, each comprising an armature winding 23 and differentially related series field windings 24 and 25. When energized from a suitable source of power as, for example, a battery 27, through winding 25, the motors 20 and 22 are caused to rotate in the voltage-raising direction and when energized through winding 24 the motors rotate in the voltage-lowering direction.

To control the operation of the regulator motors 20 and 22, in accordance with changes in the voltage of the regulated circuit, contact making voltmeters or primary relays 28 and 30 are provided. The primary relay 28, to which the relay 30 is similar, comprises fixed contact members 31 and 32 disposed in engageable relation with a movable contact member 33, the position of which is controlled by the magnitude of the voltage which energizes an operating winding 35 of the relay.

When the voltage impressed upon the winding 35 of the primary relay 28 rises above a predetermined value the contact member 33 will be moved into engagement with the contact member 31 to complete an energizing circuit for the regulator motor 20 causing it to actuate the regulator in the voltage-lowering direction. Similarly, when the voltage impressed upon the relay winding drops below a predetermined value, engagement

of contact members 33 and 32 is effected to operate motor 20 in the voltage-raising direction.

It will thus be seen that the regulator 10 will be operated to maintain at a constant value the voltage which energizes its primary relay 28. In a similar manner, the regulator 12 will also be operated to maintain at a constant value the voltage which energizes its primary relay 30.

Voltages for controlling the primary relays 28

10 and 30 are respectively supplied through potential transformers 38 and 39 which are respectively energized in the manner shown by potentials E_{ba} and E_{bc} appearing between the lines of the transmission circuit at the location of the regulators.

15 To compensate the voltage drop which occurs in the transmission circuit between points K and D, which impedance is schematically represented as a resistor R and an inductor X in each of the circuit lines, the voltage-modifying or compensating equipments 40 and 41 are utilized in association with the primary relay energizing circuits.

Equipment 40 comprises a resistor element 43 and an inductor element 44 connected intermediate potential transformer 38 and the primary

20 relay 28. Through a portion of each of elements 43 and 44, adjustable by means of tap connections 60 and 61 associated therewith, is circulated, from a current transformer 46, a current which is proportional to the current I_a flowing in the circuit conductor A. In a similar manner, equipment 41 comprises a resistor element 47 and an inductor element 48 through which a current transformer 49 circulates a current proportional to the current I_c flowing in transmission circuit conductor C.

25 As illustrated by the vector diagram of Fig. 2, in which voltages E_a , E_b and E_c represent the equivalent star or Y connection voltages impressed by a supply source (not shown) upon the conductors or lines A, B and C of the transmission

30 circuit and I_a , I_b and I_c the currents flowing in conductors A, B and C at a given value of unity power factor load. The line-to-line voltage E_{ba} which energizes transformer 38 has such a phase position that assuming a phase rotation of

35 A—B—C, current I_a lags it by 30° and line-to-line voltage E_{bc} which energizes the transformer 39 has such a phase position that current I_c leads it by 30° .

The vector diagram of Fig. 3 illustrates, when 40 the circuit conditions are as given by the diagram of Fig. 2, the voltage drops which occur in that portion of the line between the regulators, or point K, and a distant center of distribution, designated by D, at which it is desired that the regulators maintain constant the circuit voltage.

This circuit voltage to be held constant is designated at E'_{ba} for the value appearing between lines A and B and E'_{bc} for the value appearing between lines B and C. It will be noted that the resistance component of line drop RI and reactance component XI combine to form the total impedance drop E_{kd} which vectorially combines with E'_{ba} to produce E_{ba} and with E'_{bc} to produce E_{bc} .

45 In order that the regulators 10 and 12 may function to maintain constant the circuit voltage at the center of distribution D, it is necessary that primary relay 28 be influenced by a voltage equivalent to E'_{ba} and that relay 30 similarly be influenced by a voltage equivalent to E'_{bc} . In the past, this desired result has been attained by energizing each compensator by a current which at unity power factor is in phase with the voltage acting in the primary relay circuit.

50 In other words past practice has been to set the

resistance and reactance elements of the compensator so that the voltage drops through them set up by the compensator energizing current will be respectively proportional and equivalent to the voltage drops which occur in the circuit or line to be compensated due to the resistance and reactance components of the line impedance. The auxiliary equipment necessary, as already explained, to provide the desired in-phase relation, in an open delta installation of two single phase regulators with a three phase transmission circuit, has materially increased the expense and complication of the complete compensating equipment.

55 In order to eliminate this added expense and complication, I utilize, as before mentioned, the 30° displaced line current directly available at each regulator to energize the compensator and I so modify the settings of the resistance and reactance elements thereof that the error introduced by the displaced current is corrected, thereby allowing the compensation to be an exact equivalent of that attainable in the prior art in-phase energization system explained.

60 To more fully explain the special expedients of my invention, the vector diagrams of Figs. 4, 5 and 6 may be referred to. In the diagram of Fig. 4 which is a substantial reproduction of Fig. 3, it will be seen that the line impedance drop vector E_{kd} instead of being made up of the two components RI and XI of Fig. 3, may in the case of the compensator associated with regulator 10 in transmission line A be made up of a modified vector $r_1 I_a$ which is in phase with line current I_a and a modified vector $x_1 I_a$ displaced 90° therefrom. That is, for the situation in which the energizing current I_a of the compensator 40 of Fig. 1 lags the associated line-to-line voltage E_{ba} by 30° , it is only necessary to reduce the setting of resistor element 43 and increase the setting of reactance element 44 to obtain the same results as are obtainable through the usual in-phase current energization of the compensator.

65 Likewise, in the case of compensator 41 associated with the regulator 12 in transmission line C, the desired impedance drop E_{kd} may be obtained when the compensator is energized by line current I_c which leads the associated line-to-line voltage E_{bc} by 30° by changing the setting of resistance element 47 to provide a modified vector $r_2 I_c$ in phase with the line current and reducing the setting of reactance element 48 to provide a modified vector $x_2 I_c$.

70 In arriving at the proper values of these modified compensator element settings, the settings in accordance with the prior art method, in which the compensator is energized by a current which is in phase with the primary relay circuit energizing voltage at unity power factor of the regulated circuit load, are first determined. In accordance with this prior art method, the compensator is set for an impedance having a magnitude equivalent to the value of impedance in the line to be compensated for and an angle equal to the angle of that line impedance. In other words, the settings of the resistance and reactance elements are so made that the voltage drops through them will be respectively proportional and equivalent to the voltage drops which occur in the power circuit or line due to the resistance and reactance components of its impedance.

75 These prior art values having been determined, modification thereof is then made, for the system of this invention in which the compensator is en-

ergized by a current which at unity power factor is displaced 30° from the primary relay circuit energizing voltage, in the following manner:

For the case in which the current lags the voltage by 30° , typified by compensator 40 in the showing of Fig. 1, the compensator is set for an impedance having a magnitude equivalent to the value of the line impedance and having an angle 30° greater than the angle of the line impedance. Such a setting may be obtained as reference to Fig. 5 will presently indicate, by multiplying the setting that would be made were the compensator energizing current in phase with the voltage at unity power factor by $(0.866+j0.5)$.

15 Thus

$$r_1+jx_1 = (0.866+j0.5)(R+jX) \\ = (0.866R-0.5X)+j(0.866X+0.5R)$$

In the above expressions j is the well known complex quantity factor applicable to vector analysis, r_1 and jx_1 are respectively the proper settings for the resistance and reactance elements of the compensator for the 30° lagging current, and R and jX are the usual settings of the elements, when the compensator is energized by an in-phase current at unity power factor.

This relation is more clearly depicted by the vector diagram of Fig. 5, in which angle L_1 represents the phase angle of the line impedance for the particular values of resistance and reactance components assumed in the vector diagrams of Figs. 3 and 4. The proper setting of the elements of the compensator 40, when energized by the lagging current I_a , is such that its phase angle 35 will be L_1+30° or G_1 .

For the case in which the compensator energizing current leads the voltage by 30° , which is typified by compensator 41 in the system of Fig. 1, the compensator should be set for an impedance 40 having a magnitude equivalent to the value of line impedance and having an angle 30° less than the value of the line impedance. Such a setting may be obtained by multiplying the setting that would be made were the compensator energizing current 45 in phase with the voltage at unity power factor by $(0.866-j0.5)$. Thus,

$$r_2+jx_2 = (0.866-j0.5)(R+jX) \\ = (0.866R+0.5X)+j(0.866X-0.5R)$$

50 In the above expression, r_2 and jx_2 are, respectively, the proper settings of the resistance and reactance elements of the compensator when its energizing current leads the voltage by 30° and R and jX are the usual settings of the compensator 55 when it is energized by an in-phase current.

The above relation is vectorially depicted by the diagram of Fig. 6, in which the special settings of the compensator energized by the 30° leading current I_c are such that the phase angle 60 G_2 of its impedance has a value 30° less than that of the line impedance angle L_1 .

That these special settings are satisfactory for changing values of regulated circuit power factor will be apparent from an inspection of the 65 vector diagrams of Figs. 7 and 8, which are drawn to illustrate conditions of lagging and leading load currents, respectively. In Fig. 7, for example, in which currents I_a , I_b and I_c are shown as lagging the corresponding phase voltages by an angle alpha, the compensator impedance triangles, which cause the regulators to boost the circuit supply of voltages by values sufficient to compensate for the line drop, are rotated through a corresponding angle, thereby 75 accounting for the greater illustrated difference

between voltages E'_{ba} and E_{ba} controlled by regulator 10 in the system of Fig. 1, and voltages E'_{bc} and E_{bc} controlled by regulator 12.

Likewise, in the case of a leading power factor load shown in Fig. 8, by a similar displacement in the leading direction of the line currents I_a , I_b , and I_c , the compensator impedance triangles are correspondingly rotated in the opposite direction to cause the regulators to reduce the supply voltages E_{ba} and E_{bc} to values necessary to maintain constant the voltages E'_{ba} and E'_{bc} at the distant center of distribution. Hence, while the original discussion has assumed unity power factor, it will be seen that the conclusions may be extended to any power factor as the system still permits the compensating voltage that is introduced in the relay circuit to appropriately vary with the power factor.

Since the system requires that the phase angle of the compensator impedance be rotated 30° with respect to the impedance angle of the line to be compensated, negative resistances may be encountered in increasing the phase angle when the regulator is connected to open-air lines typified by the vector diagram of Fig. 9, and negative reactances may be encountered in decreasing the phase angle when the regulator is connected to cable circuits typified by the vector diagram of Fig. 10.

Fig. 9 represents a line or circuit having a large 105 value of reactance X' as compared with its resistance R' , thereby producing a line impedance phase angle L_2 , which is in excess of 60° . For this condition, the proper angle for the setting of a compensator energized by a 30° lagging current 110 is L_2+30° or G_3 . Since G_3 is in excess of 90° , the resistance component r_3I_a must be negative, as illustrated, the reactance component x_3I_a remaining positive as before.

Similarly, when the line to be compensated 115 possesses such a low value of reactance X'' as compared with its resistance R'' that the impedance L_3 is less than 30° , as shown in Fig. 10, an energization of the compensator by a 30° leading current I_c necessitates that the reactance component x_4I_c of the compensator impedance be 120 negative, in order that the angle of the compensator G_4 may be of the proper value required for this condition. The resistance component r_4I_c of the compensator impedance is positive as before.

The explained conditions in which negative values of compensator resistance and reactance are required necessitate that the compensator devices utilized in the system of my invention be 130 capable of providing these negative values in addition to the usual positive values. A compensator possessing this characteristic is disclosed and claimed in a copending application Serial No. 659,163, by E. R. Wolfert, filed March 1, 1933, and 135 assigned to the same assignee as this invention. The compensator there described is inherently capable of providing both negative and positive values of resistance and reactance.

However, when no such improved device is 140 available, compensators capable only of positive values may be modified in accordance with the showings of Figs. 11 and 12 to fulfill the above stated requirement. In Fig. 11, the simplified compensator shown at 40 in the system of Fig. 1 145 is illustrated. Intermediate the resistance and reactance elements 43 and 44 of this compensator and the energizing circuit for winding 35 of primary relay 28 are disposed reversing switches 56 and 58. When the blades of these two switches 150

are closed to the upward position, as illustrated in Fig. 11, the compensator circuits are connected to supply positive values of components to the energizing circuit of the relay. Movement 5 of the blades of switch 58 to the downward position reverses the terminal connections of resistance element 43, thereby, in effect, causing the voltage drop across this element to act negatively in the relay circuit, as is required for the conditions depicted in Fig. 9. Similarly, a movement 10 of the blades of switch 58 to the downward position effects a reversal of the connections of reactance element 44, thereby supplying the negative value of the reactance component required when 15 the circuit conditions are as depicted by Fig. 10.

Fig. 12 illustrates a compensator known in the art as the rotary contactless type in which the reversing switch is applied. Instead of providing the resistance and reactance elements thereof 20 with tap connections, shown at 60 and 61 for the compensator 40 of Figs. 1 and 11, the device of Fig. 12 utilizes two variometer assemblies 63 and 64, each of which comprises a plurality of inductively adjustable windings more completely described in U. S. Patent No. 1,858,845, issued to E. R. Wolfert May 17, 1932, and assigned to the same assignee as this invention. With this particular compensator, the reversing switches 58 and 58 perform exactly the same function as in 30 the case of compensator 40 of Fig. 11.

The compensating system thus far described involves no control circuit connections between the two regulators disposed in delta relation in the three-phase transmission circuit, but, in certain 35 cases, may require, as has been seen, a compensator element reversing switch. Additional schemes involving no reversing devices, but requiring control-circuit connections between the regulators, are shown in Figs. 13 and 15. These 40 two systems possess a further advantage in that a similar setting of the compensators for both regulators may be made. The three-phase power circuit and the regulators 10 and 12, with which they are illustrated, will be seen to be an exact 45 reproduction of the showing of Fig. 1.

The system of Fig. 13 is especially useful when it is known that the line or circuit to be compensated possesses characteristics giving it an impedance angle which is greater than 60°. By 50 interconnecting the two current transformers 46 and 49 in the manner shown, both compensators 40 and 41 may be supplied by a current which leads the associated line-to-line voltage by 30° at 55 unity power factor of the regulated circuit load. This relation is illustrated by the vector diagram of Fig. 14.

Compensator 41 is energized, as in Fig. 1, directly by the current I_a supplied through current transformer 49. This current leads by 30° the voltage E_{ba} , which energizes the actuating winding of primary relay 30. Compensator 40, however, is, by virtue of the interconnections 66 and 67 between the two current transformers, energized by the vector sum of currents I_a and I_c , which combined current, equivalent to I_b , is reversed before being impressed upon the compensator in order that it may lead the voltage E_{ba} , which energizes the energizing winding of relay 28, by 30°. This reversed current is indicated in 70 the diagram by vector—($I_a + I_c$).

As a result of this similarity in phase position and magnitude of the two compensator energizing currents, compensator 40 may be set in exactly the same manner as is compensator 41, which 75 manner has already been explained in detail. In

addition to permitting of a similar setting for the two compensators, which is for 30° less than the line impedance angle, the necessity for utilizing negative values of compensator components is eliminated.

In the modification of Fig. 15, a similar expedient is utilized to cause the energizing currents of both compensators 40 and 41 to lag the associated line-to-line voltages by 30°. This particular interconnection of current transformers is especially useful when it is known that the impedance angle of the line to be compensated is less than 30°. By virtue of interconnections 66 and 67' between the current transformers 46 and 49, compensator 41 is supplied with the sum of currents $I_a + I_c$ reversed, as indicated at—($I_a + I_c$) in the vector diagram of Fig. 16, compensator 40 being energized in the usual manner directly by the current I_a through current transformer 46.

It will be apparent that both of the compensators may now be set for a phase angle 30° greater than the impedance angle of the line, and, further, that the need for negative values of resistance and reactance is, under the conditions named, effectively eliminated.

In all of the foregoing analysis, a phase rotation A—B—C has been assumed.

Although I have shown and described certain specific embodiments of my invention, I am fully aware that many modifications thereof are possible. My invention, therefore, is not to be restricted except insofar as necessitated by the prior art and by the scope of the appended claims.

I claim as my invention:

1. In combination, an alternating-current power circuit in which the line current, at unity power factor, is displaced a given angle from the line-to-line voltage of the circuit, a regulator disposed to control the voltage of said circuit, a primary relay for controlling the operation of said regulator, a circuit for energizing said relay by a measure of the said line-to-line voltage, a line-drop compensator comprising a resistance element and a reactance element disposed in said relay energizing circuit, and means for energizing said compensator by a measure of the said power-circuit line current, the elements of the compensator being so adjusted that the compensator impedance has a phase angle differing from that of the power circuit impedance by the said given angle of displacement of the line current from the line-to-line voltage of the power circuit at unity power factor.

2. In combination, a voltage regulator disposed in an alternating-current power circuit in which the line current, at unity power factor, is displaced a given angle from the line-to-line voltage, said regulator having an operation-control relay and an operating circuit therefor that is supplied with a voltage that varies in accordance with the said line-to-line voltage, a circuit-impedance drop compensator, energized by the said line current, comprising a resistance element and a reactance element disposed in said relay energizing circuit, the elements of the compensator being so set that they present an impedance equivalent to that of the power circuit the voltage drop through which is to be compensated and having a phase angle differing from that of the said power circuit impedance by the said given angle of displacement at unity power factor of the power-circuit line current with respect to the power-circuit line-to-line voltage.

3. In combination, a pair of voltage regulators 150

- connected in open-delta relation in a three-phase power-transmission circuit, each of said regulators having an operation-control relay with an energizing circuit therefor which is supplied by a measure of the associated line-to-line voltage of the circuit, a line-drop compensator comprising a resistance element and a reactance element disposed in the energizing circuit of each of said relays, and means for energizing one of said compensators by a measure of the power-circuit line current which, at unity power factor, lags the line-to-line voltage supplying the associated relay by 30°, the elements of the compensator being so adjusted that the compensator impedance has a phase angle which is 30° greater than that of the power circuit impedance the voltage drop through which is to be simulated by the compensator.
4. In combination, a pair of voltage regulators connected in open-delta relation in a three-phase power-transmission circuit, each of said regulators having an operation-control relay and an energizing circuit therefor that is supplied with a voltage that varies in accordance with the associated line-to-line voltage of the circuit, a line-drop compensator comprising a resistance element and a reactance element disposed in the energizing circuit of each of said relays, and means for energizing one of said compensators by a measure of the power-circuit line current which, at unity power factor, leads the line-to-line voltage supplying the associated relay by 30°, the elements of the compensator being so dimensioned that the compensator impedance has a phase angle which is 30° less than that of the power circuit impedance the voltage drop through which is to be simulated by the compensator.
5. In a system comprising two voltage regulators connected in open-delta relation in a three-phase power-transmission circuit, each of said regulators having an operation-control relay and an energizing circuit therefor that is supplied in accordance with the associated line-to-line voltage of the power circuit, the combination with each regulator, of a circuit-impedance-drop compensator, energized by a measure of the current flowing in the regulator-connected line of the power circuit, comprising a resistance element and a reactance element disposed in the said energizing circuit for the relay of that regulator, the elements of the compensator whose energizing current lags, at unity power factor, the associated relay supply voltage by 30° being so adjusted that the compensator impedance has a phase angle which is 30° greater than the angle of the power-circuit impedance the voltage drop through which is to be simulated in the relay-energizing circuit by the compensator.
6. In a system comprising two voltage regulators connected in open-delta relation in a three-phase power-transmission circuit, each of said regulators having an operation-control relay and an energizing circuit therefor that is supplied in accordance with the associated line-to-line voltage of the power circuit, the combination, with each regulator, of a circuit-impedance-drop compensator, energized by a measure of the current flowing in the regulator-connected line of the power circuit, comprising a resistance element and a reactance element disposed in the said energizing circuit for the relay of that regulator, the elements of the compensator whose energizing current leads, at unity power factor, the associated relay supply

voltage by 30° being so set that the compensator impedance has a phase angle which is 30° less than the angle of the power-circuit impedance the voltage drop through which is to be simulated in the relay-energizing circuit by the compensator.

7. In a system comprising two voltage regulators connected in open-delta relation in a three-phase power-transmission circuit, each of said regulators having an operation-control relay and an energizing circuit therefor that is supplied in accordance with the associated line-to-line voltage of the power circuit, the combination, of a circuit-impedance drop compensator for each regulator energized by a measure of the current flowing in the regulator-connected line of the power circuit, comprising a resistance element and a reactance element disposed in the said energizing circuit for the relay of that regulator, the elements of the compensator whose energizing current lags, at unity power factor, the associated relay supply voltage by 30° being so set that the compensator impedance has a phase angle which is 30° greater than, and the elements of the compensator whose energizing current leads, at unity power factor, the associated relay supply voltage by 30° being so set that the compensator impedance has a phase angle which is 30° less than the angle of that portion of power circuit impedance the voltage drop through which is to be corrected by the compensators.

8. In a system comprising two voltage regulators connected in open-delta relation in a three-phase power-transmission circuit, each of said regulators having an operation-control relay and an energizing circuit therefor that is supplied in accordance with the associated line-to-line voltage of the power circuit, the combination, with each regulator, of a line-drop compensator, energized by a measure of the current flowing in the regulator-connected line of the power circuit, disposed in the said energizing circuit for the relay of that regulator, the compensator whose energizing current lags, at unity power factor, the associated relay supply voltage by 30° being so set that its impedance has a phase angle which is 30° greater, and the compensator whose energizing current leads, at unity power factor, the associated relay supply voltage by 30° being so set that its impedance has a phase angle which is 30° less, than the angle of that portion of power circuit impedance the voltage drop through which is to be corrected by the compensators, the magnitude of each compensator impedance being equivalent to the impedance of the said portion of the power circuit.

9. In a regulating system comprising two voltage-adjusting means connected in open-delta relation in a three-phase power-transmission circuit, each of said adjusting means having an operation-control relay and an energizing circuit therefor that is supplied with a voltage that varies in accordance with the associated line-to-line voltage of the power circuit, and a line-drop compensator disposed in each relay-energizing circuit, the combination of compensator-energizing means comprising a current transformer in each of the power-circuit lines in which the said voltage-adjusting means are connected, the compensator associated with the line in which, at unity power factor, the power current lags by 30° the associated line-to-line voltage being energized by the current supplied through the current transformer in that line, and the compensator associated with the other line in which,

at unity power factor, the power current leads by 30° the associated line-to-line voltage, being energized by the reversed sum of the currents supplied through both of said current transformers, said summation current reversed thus also lagging by 30° the compensator-associated line-to-line voltage of the power circuit.

10. In a regulating system comprising two voltage-adjusting means disposed in open-delta relation in a three-phase power-transmission circuit, each of said adjusting means having an operation-control relay and an energizing circuit therefor that is supplied from the associated line-to-line voltage of the power circuit, and a line-drop compensator disposed in each relay-energizing circuit, the combination of compensator-energizing means comprising a current

transformer in each of the power-circuit lines in which the said voltage-adjusting means are connected, the compensator associated with the line in which, at unity power factor, the power current leads by 30° the associated line-to-line voltage being energized by the current supplied through the current transformer in that line, and the compensator associated with the other line in which, at unity power factor, the power current lags by 30° the associated line-to-line voltage, being energized by the reversed sum of the currents supplied through both of said current transformers, said summation current reversed thus also leading the compensator-associated line-to-line voltage of the power circuit.
